United States Patent Office

Des. 202,192
Patented Sept. 7, 1965

202,192

CHRISTMAS TREE ORNAMENT OR SIMILAR ARTICLE

Jack Burnbaum, 451 D St., Newton, Mass.

Filed Jan. 12, 1965, Ser. No. 83,400

Term of patent 14 years

(Cl. D29—1)

Fig. 1.

Fig. 2.

Fig. 3.

Fig. 4.

FIG. 1 is a top plan view of a Christmas tree ornament showing my new design;

FIG. 2 is a front elevational view thereof, the back thereof being similar in appearance;

FIG. 3 is a side elevational view taken at a right angle to FIG. 2, the side opposite thereto being similar in appearance; and

FIG. 4 is a fragmentary perspective view, partly in section, of a portion thereof.

I claim:

The ornamental design for a Christmas tree ornament or similar article, substantially as shown and described.
